Primary Examiner—T. Chase Nelson*Assistant Examiner*—Karen Acker(74) *Attorney, Agent, or Firm*—Richard D. Clarke(57) **CLAIM**

I claim the ornamental design for a container for dispensing garments, as shown and described.

DESCRIPTION

FIG. 1 is a perspective view of the container for dispensing garments;

FIG. 2 is a front view of the container for dispensing garments;

FIG. 3 is a rear view of the container for dispensing garments;

FIG. 4 is a bottom view of the container for dispensing garments;

FIG. 5 is a top plan view of the container for dispensing garments;

FIG. 6 is a side view of the container for dispensing garments; and,

FIG. 7 is a side view of the container for dispensing garments.
